Patented Feb. 16, 1926.

1,573,066

UNITED STATES PATENT OFFICE.

ROSI LAMP'L, OF BERLIN, GERMANY.

POLYCHROMATIC SECURITY PRINT.

No Drawing.

Application filed April 27, 1921. Serial No. 465,032.

(GRANTED UNDER THE PROVISIONS OF THE ACT OF MARCH 3, 1921, 41 STAT. L., 1313.)

To all whom it may concern:

Be it known that I, Rosi LAMP'L, née MÜLLER, residing at 24 Meinekestrasse, in the city of Berlin, Germany, have invented 5 certain new and useful Improvements in Polychromatic Security Prints (for which I have filed applications in Germany, July 22, 1919, Patent No. 362,878; in England, January 10, 1921, Patent No. 157,811; in Spain, 10 March 29, 1921, Patent No. 77,632; in Sweden, March 21, 1921, Serial Number 1096/26; in Austria, March 11, 1921, Serial Number A. 1358-21; in Hungary, March 21, 1921, Serial Number L. 4811; in Italy, 15 March 17, 1921, Patent No. 196,151; in Switzerland, February 28, 1921, Patent No. 95,082; in Poland, March 30, 1921, Serial Number 8441/3337; in France, March 31, 1921, Patent No. 538,638; in Belgium, March 20 29, 1921, Patent No. 295,009; and in Czechoslovakia, March 17, 1921, Serial Number P. 11728/21), of which the following is a specification.

My invention refers to polychromatic security prints and the like containing different designs each in a color distinctive to the eye and of such character as will make it difficult or impossible to reproduce the securities by any photographic process.

30 In the specification to U. S. A. Patent 776,515 it has been proposed to prevent photomechanical reproduction of safety composite-color prints by employing for different and adjoining designs distinctive 35 colors, the spectrum of absorption of one color comprising that of the other, the effect being, that the two different designs will never appear separately on any photographic negative, thus making it impossible 40 to obtain a separate negative for each different design. However in this case the two different designs appear in different degrees of blackening on the negatives and their line of division of the adjoining parts 45 is therefore distinctly visible, thus enabling the falsifier to correct those negatives by hand and to obtain a negative with only one design.

50 This disadvantage is however avoided when printing the two different and adjoining designs with such colors, which although being well differentiated to the eye always produce about the same degree of blackening on the negative when photographing

the print with or without any color filtering means. No line of division of the adjoining parts is to be seen on the negative and therefore no corrections can be made by hand. It will easily be understood that the difficulties of falsifying securities are much 55 greater, when their designs are printed with colors, producing about equal degrees of blackening on the photographic negative that is with colors having about equal degrees of photographic luminosity. 65

My invention is applicable to a great variety of different colors and color combinations from different sources and manufacturers. Merely as instances of carrying the invention into practice I may mention the 70 following examples of procedure in applying the different colors or hues.

No. 1. As a ground color I may use, an aniline green, known in the market as No. 3266 (510) green of the color catalogue of 75 Kast & Thinger of Stuttgart, Germany; and in combination therewith for use as a design color, an aniline blue, known as steel blue O (196) of the same color-catalogue.

2. For use as a ground color, an aniline red 80 No. 4876 (541) known as bronze red in the said color catalogue; and as complement as a design color, an aniline brown, known as solid brown lake, middle, (No. 515) in the color catalogue of E. T. Gleitmann, Dresden, Germany. Further, for use as a ground color an aniline green known as post green (No. 602) in Gleitmann's color catalogue;

and complementary thereto as the design color, an aniline violet known as violet lake, 85 dark (No. 308), in the said Gleitmann's color-catalogue. 4. Further, for use as the ground color, an aniline violet, known as brilliant violet bluish II, No. 292 in Gleitmann's color catalogue, and complementary 90 for use as the design color, an aniline brown, known as photographic brown II in Gleitmann's color catalogue. 5. Similarly, for discharge printing I may use as the ground color, a composite color consisting of 65% 100 guinea-green and 35% mandarine-yellow; this is a pure and rich dark green. Complementary thereto, for use as a design color

(which is employed as the discharge or etching liquor) a composite color consisting of 105 98%, mandarine yellow and 2% guinea-green, which presents in appearance a pure rich yellow or orange hue, but when

printed on the ground color referred to, this discharge changes to a very dark olive green. The components of this last example are aniline colors made and sold by 5 the firm "Actiengesellschaft für Anilinfarbenfabrikation of Berlin, SO. 36, Germany."

I wish it to be understood, however, that I am by no means restricted to these different colors and color combinations; nor do I 10 wish to be understood to say that the firms referred to are the only dealers and manufacturers from whom suitable inks or colors may be obtained, inasmuch as obviously any other dealer or manufacturer may be in position 15 to supply suitable pigments. It will, however, obviously be necessary to ascertain by preliminary tests in each case, which colors, dyes or pigments, while possessing the desired distinctness to enable the design 20 to be easily perceived by the human eye, possess also the necessary similarity of photographic luminosity.

In carrying this invention into practice, any of the different ways of coloured printing or polychromatic printing may be used. 25 For instance a multicoloured design may be provided on a neutral paper, cloth, or other base, whereby at least on a portion of the object to be printed, the different lines or 30 points, which are printed in two or more colours, should be as close as possible to each other, so as to render impossible a subsequent colouring retouch of any photographic copy. It is further possible to produce the 35 desired multicoloured effect by using a tinted or toned paper or by printing first a priming of one colour on the paper or the like, whereafter the given design in another colour or in several more colours is printed on 40 the first priming ground or on the tinted paper. The colours of the first tinting or priming process and those of the subsequent design-making colors are selected as stated above, so as to possess the same photographic 45 luminosity, although they look quite different to the eye of the contemplating person. The same result can be obtained also, if a tinted paper, or a paper which has been printed first by a priming plate, is printed 50 thereupon with an etching-design, as it is usual in cloth-printing and in calico-printing. In carrying through this process the etching liquor or the discharges are prepared in such a manner that resists or colors 55 are added to the liquor which are not acted

upon by the etching medium, and mordants or other color fixing agents may also be added, so as to produce multicolored designs upon the background. The colors or various hues, produced by the etch-printing, must be chosen in accordance with the colours of the priming or basic material, in so far as they must have the same or nearly the same photographic luminosity, as it had been explained above. 60 Again the same result can be obtained by printing several colours of different photographic luminosity one on the other, if only care is taken, that the mixture or combination of the component colours results in such 65 definitive colour-tints, which have exactly or nearly the same photographic luminosity. Another possible application of the invention would consist therein that a negative and a positive print of the same design in 70 the above stated colours are printed one on the other in such an exact manner, that thereby the printed picture is produced.

The before described printing method can be combined with the ordinary method in use 80 until now, as on account of the fact; that a portion of the picture, being prepared according to the invention, can not be photographed, the entire print cannot be counterfeited.

I claim:

1. A polychromatic security print and the like comprising adjoining designs, each in a distinctive color, said colors producing about the same degree of blackening of the 90 negative, when photographing the print without and with any color filtering means.

2. A polychromatic security print and the like comprising partially overlapping designs, each in a distinctive color, said colors 95 producing about the same degree of blackening of the negative, when photographing the print without and with any color filtering means.

3. A polychromatic security print and the like comprising a colored underground and a design superimposed thereon in a distinctive color, the underground and the design producing about the same degree of blackening of the negative, when photographing the 105 print without and with any color filtering means.

In testimony whereof I affix my signature.

ROSI LAMP'L.
